VACUUM CLOSING MACHINE

Milton E. Robinson and Richard N. Henderson,
Waukegan, Ill., assignors to American Can
Company, New York, N. Y., a corporation of
New Jersey

Application April 5, 1941, Serial No. 387,090

3 Claims. (Cl. 226—82)

This invention relates to a vacuum closing machine for friction top containers and has particular reference to closing and sealing a filled container wherein the top of such a container with a friction plug cover loosely assembled, is temporarily sealed so that the air from within the head space may be evacuated just prior to insertion of the plug cover which seals the container, the vacuumizing and sealing operations being performed during a single downward travel of suitable pressure sealing devices.

It is a usual practice to pack paints, enamels and similar products in friction top containers. This type of container is easy to close after being filled, is simple to open by an ultimate consumer and may thereafter be reclosed to preserve any remaining contents. Such containers must ordinarily be of sufficient capacity to provide space for a unit measure of the product and also to allow head space to prevent the oils and thinners contained in the paints from being forced out between the friction walls of the ring and the plug cover by any increase in the internal pressure of the closed container. Such pressure increases are likely to occur in the entrapped air of sealed cans as the result of temperature changes. Any reduction in the oil or thinner contents by leakage will vary the proportion of the ingredients of the product, as originally intended, thus adversely affecting its quality.

A larger size container for a unit quantity would leave an increased head space and might avoid paint can leakage but this would require more sheet material and consequently would involve added cost for each container. An increase in head space is also conducive to a more rapid drying out of the surface of the paint and result in formation of a skin which cannot be used and which would be an unnecessary waste. If such a layer or skin is not entirely removed prior to mixing the product for use and is stirred into the contents undesirable roughened particles in the coating results.

The present invention contemplates the closing of conventional types of containers requiring a minimum head space for a given quantity of material and wherein the product substantially fills the container, the sealing of which takes place in an improved machine which overcomes all of the above mentioned difficulties.

An object of the invention is the provision of a machine for vacuumizing, closing and sealing filled friction type containers which have their plug covers loosely assembled, such a machine having a sealing head and a pressure chuck each

of which moves through a complete cycle. On the downward stroke of such a cycle the sealing head initially engages with the peripheral edge of the container, then the air from the interior of the sealing head and the head space within the container is rapidly exhausted, following which the plug cover is inserted into sealed position, the vacuum in the sealing head broken and the chuck and then the head lifted.

Another object of the invention is the provision of adjusting means in a machine of the character described wherein containers of different heights may be closed by a simple adjustment in the vertical position of the pressure chuck shaft which controls the movement of the sealing head and pressure chuck.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a vacuum closing machine embodying the present invention with parts broken away and with parts shown in section and showing a friction plug container with a cover loosely applied just prior to being placed into a position for sealing;

Fig. 2 is a vertical sectional detail of a vacuum valve shown in Fig. 1 as viewed along the line 2—2 of said figure, and showing a slide of the valve in an outward position with the valve open to the atmosphere;

Fig. 3 is a view similar to Fig. 2 showing the position of the slide when evacuating the air from the sealing head and head space of a container;

Fig. 4 is a vertical sectional view of the valve and the slide taken substantially along the broken line 4—4 in Fig. 3, showing the valve connection that leads to the vacuum source;

Fig. 5 is a front elevation of the vacuum closing machine shown in Fig. 1 and illustrating the closing and vacuumizing mechanism;

Fig. 6 is an enlarged fragmentary view, partly in vertical section, of a sealing head in position against the upper double seam of a friction top container, illustrating sealing off a chamber adjacent thereto and showing the plug cover loosely resting on the container and spaced beneath a pressure closing chuck disposed in raised position prior to sealing the container; and

Fig. 7 is a view similar to Fig. 6 showing the pressure closing chuck in its lowered position

and against the friction plug cover following a closing and sealing operation.

As a preferred embodiment of the invention the drawings illustrate the principal parts of a vacuum closing machine for vacuumizing, closing and sealing friction top containers. Such a container may be of the multiple friction wall variety.

The vacuum closing machine comprises a machine main frame 11 having front brackets 12, 13 and 14 and a rear bracket 15. The lower front bracket 12 serves as a table or platform upon which a filled friction top container 16, with a plug cover 17 loosely applied may be positioned for sealing. The intermediate bracket 13 and the upper bracket 14 extend from the main frame in parallel alignment to form suitable mountings for a pressure chuck shaft 18. This shaft has reduced sections 19 and 22 at its lower end. The lowermost smallest section 19 is threadedly connected with a pressure chuck or plate 24, while the other section 22 serves as a stem upon which a movable sealing head 25 is carried.

The pressure closing chuck 24 consists of a frusto-conical shaped member having a flat bottom surface of a diameter equal to or greater than the diameter of the friction plug cover 17. It is movable within the sealing head 25 to engage the top surface of the plug and to press it into the friction ring of a filled container.

The sealing head 25 is preferably a cast hollow bell like member having its main body part sloping outwardly and downwardly and terminating in a vertical depending wall or skirt 26. The top of the sealing head has a neck 27 and an annular ledge 28 at its base which position and support a compression spring 29. A ring 32 is assembled on the reduced section 22 of the chuck shaft against a shoulder 33 of the shaft. This supports the upper end of the spring 29. The sealing head 25 is thus normally held against the pressure chuck 24 (Fig. 1).

The depending wall or skirt 26 on the sealing head 25 has an internal annular recess 34 (Figs. 1, 6 and 7) which is rectangular in cross section and which is adapted to receive a rubber ring or sealing pad 35, also rectangular in cross section. Such a ring or pad is adapted to engage the top annular edge or double seam of the container 16. The inner surface of the wall 26 of the head is cut away and flared as at 36. This enlarges the opening and facilitates centering of the container top.

A vertical stem or connection 37 is integral with a boss or lug 38 on the sealing head 25 (Fig. 1). This stem is adapted to slide within a vacuum and air valve confined in a casing 39 indirectly carried on the frame of the machine. A suitable opening 42 in the stem 37 of the sealing head (Figs. 1, 2, 3 and 4) serves as a passageway for admitting and evacuating air from the sealing head as will be hereinafter explained.

The upper front side of the pressure chuck shaft 18 is slotted at spaced intervals as at 43 to set off a plurality of rack teeth 44 therebetween. A pinion 45 is suitably mounted in an adjustment block 46 and is arranged to have its teeth engage with the shaft teeth 44 in a rack and pinion connection (Figs. 1 and 5).

Pinion 45 is secured on a shaft 47 which is formed with a shoulder or portion of enlarged diameter 48 at one end. A pin 49 is radially disposed in this shouldered part and is adapted to be moved by hand to turn the parts carried on the shaft including the pinion 45, to raise or

lower the pressure chuck shaft 18 through the rack and pinion connection. This is to permit adjustments for can heights. A locking screw or stud 52 is threadedly connected in the adjustment block and this may be used to lock the adjustment block to the shaft after proper adjustment is made.

A cam roller 53 is mounted on the adjustment block 46 and is operable in a cam track, groove or runway 54 of a composite face and edge cam 55. This cam is mounted on one end of a horizontal drive shaft 56 which is journaled in the machine main frame 11. The face of the cam through its track 54 is adapted to reciprocate the sealing and closing mechanism in unison, while a peripheral edge or track 57 of the cam is designed to operate the vacuumizing mechanism.

The edge or track 57 provides the cam surface for a cam roller 58 which is carried on one end of a cam lever 59. The lever is pivotally mounted upon a lug 62 which may be an integral part of the frame 11. The lower end of the lever has an elongated slot 63 in which a valve slide lug 64 is connected. A stud or pin 65 forms a pivotal connection for the lever and the slide lug. Such a lug extends from one end of a tubular slide valve 66 constituting a movable part within the vacuum valve casing 39.

30 A cam lever tension spring 67 (Fig. 5) has one end connected to a lug 68 on the lever and its opposite end connected to a lug 69 extended from the frame 11. This arrangement maintains the cam roller 58 in operative engagement with and 35 against the cam edge surface or track 57.

The air and vacuum valve casing 39 is fixed to the lower face of the frame bracket 13 so that the stem 37 is free to move vertically in a valve chamber 72 (Figs. 1, 2, 3 and 4) as the sealing 40 mechanism is raised and lowered by the pressure chuck shaft 18. A horizontal cylindrical valve chamber 73 is formed in the valve casing 39 and the slide valve 66 is cam actuated and moved 45 therein by the cam and lever connection hereinabove described. This slide valve 66 opens and closes connection with a vacuum source which is made effective at the valve by means of a pipe 74 communicating with such source (not shown) (Figs. 1 and 4).

50 The vertical and horizontal valve chambers 72, 73 in the valve casing 39 (Figs. 2, 3 and 4) are joined by a communicating port or channel 75. The slide valve 66 also has a central chamber 76, a side port 77 and a lower or bottom port 78. The port 78 in one position of the slide valve 55 communicates with the chamber 72 by way of the port or channel 75.

Each port is adapted to be closed off at times or the side port may register with a side valve 60 vacuum port 79 cut in the casing 39, or the bottom valve port 78 with the port channel 75. When the slide valve 66 registers the ports 77 and 79 air is evacuated from the system, this including the sealing head and the container head space. This constitutes a vacuumizing step (Figs. 3 and 4). The outer section of the side valve 65 vacuum port 79 is threaded for the pipe connection 74 (Figs. 1 and 4) in turn leading as described to a proper source of vacuum.

70 When the valve slide 66 is moved to the position illustrated in Fig. 2, which takes place following a sealing operation, the vacuum source is sealed off and the port channel 75 is uncovered. A vent opening 82 disposed in an end wall 83 of the valve slide chamber in the casing 39, main-

tains communication with the outside atmosphere and when the port channel is uncovered the vacuum within the sealing head is broken.

The horizontal drive shaft 56 (Fig. 1) which rotates the composite cam 55 fixed thereon also carries a drive gear 84 at the opposite end of the shaft. This gear is continuously driven by a motor pinion 85 keyed to a motor shaft 86 of an electric motor 87. The motor is preferably conveniently mounted upon the rear bracket 15 of the machine.

A single revolution clutch 88 also is mounted on the drive shaft 56 and is arranged to intermittently operate certain parts of the machine. Such a clutch may be of the type fully illustrated in the J. G. Hodgson Patent 681,023, issued August 20, 1901, on a Power Press. Figure 1 of the drawings briefly illustrates the operating and release mechanism associated with such a clutch, part of which is mounted on the frame 11 of the machine while the remainder is connected with the gear.

A lever 89 is pivotally mounted on the main frame 11 and has an end 92 connected to the clutch operating parts. The opposite end of the lever terminates in a rounded part 93 which is adapted to slide on an inclined tail part 94 of a contact lever 95. This contact lever is pivotally mounted on the machine main frame 11 as on a stud 96.

A lower end 97 of the lever 95 is threaded to receive a threaded stud or bolt 98, the head of which is rounded off as at 99. This head serves as a contact for the filled friction top cans which press against the head when the can is placed upon the bracket 12. By pushing in the lever head, the vacuumizing, closing and sealing operations begin. Adjustment as to position of the head of the threaded stud compensates for variation in diameters of cans vacuumized and sealed by the machine.

When the container 16 is to be closed after filling, the friction plug cover 17 is loosely positioned over a friction ring 102 (Fig. 6) of the can so that a plug section 103 on the cover rests lightly in a U-shaped channel 104 of the ring. The container 16 is then placed upon the bracket 12 of the machine and is pushed rearwardly to a position directly beneath and axially of the sealing head 25. Such movement shifts the contact lever 95 to the left (Fig. 1) and thus rocks the lever 89 which immediately operates the clutch mechanism in the manner described in the Hodgson Patent 681,023 aforesaid.

The can controlled actuation and operation of the clutch permits a single rotation only of the shaft 56 which in turn effects one rotation of the composite face and edge cam 55. This cam as previously described operates both the pressure chuck shaft 18 and the valve slide 66. The motion imparted to the shaft 18 lowers the closing and sealing mechanism and during this downward stroke, the filled container is temporarily sealed off from atmosphere, is vacuumized and finally is closed.

The pressure chuck shaft 18 during its single downward stroke carries with it both the pressure chuck 24 and the sealing head 25 so that the sealing head first engages upon the peripheral edge of the container 16 to seal off the container (Fig. 6) from the atmosphere. The valve slide 66 is then moved from the position illustrated in Fig. 2 to that shown in Figs. 3 and 4 whereupon the system is directly connected with the vacuum source and the air is evacuated from the sealing

head or sealed off chamber and from the head space of the container. This action precedes engagement of the pressure chuck 24 and the plug cover 17.

5 The spring 29 carried by the sealing mechanism being yieldable, permits further motion of the pressure chuck 24 after the sealing head 25 has come to rest in its position on the container 16 (Fig. 6). The pressure chuck thus moving down against the resistance of the spring engages and inserts the plug cover 17 into the can. At the end of the down stroke (Fig. 7) the valve slide 66 is again moved out to the position illustrated in Fig. 2 and this seals off the vacuum by uncovering the port channel 75 in the valve and opening the inside of the sealing head to atmosphere. This facilitates the separation of the sealing head from the sealed container when the rising chuck, after passing through the position of Fig. 6, raises the sealing head as both members return to initial starting position. This return is made upon the upward movement of the pressure chuck shaft on the second half of the single working cycle. The sealed container 16 may then be removed from the bracket 12, replaced by another filled container and the operation repeated.

10 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being 15 merely a preferred embodiment thereof.

20 We claim:

1. A machine for vacuumizing and closing filled friction top containers, comprising a support for a filled container, a vertically movable shaft, a pressure chuck secured to said shaft, a sealing head carried by said shaft and movable with the shaft and chuck during part of a downward stroke of the shaft, a source of vacuum communicably connected to said sealing head and a valve housing having an axially reciprocable valve therein disposed between said head and vacuum source, means for moving said valve for controlling communication with said vacuum source, and means operatively connected to said valve moving means 25 and to said shaft for vertically moving the shaft relative to said container support to move said shaft downwardly to engage said sealing head with the top of a supported container having a loosely applied cover for sealing off a closed chamber including the container head space beneath said loosely applied cover and to thereafter actuate said valve moving means to establish communication between said vacuum source and said chamber to vacuumize the latter, said shaft being operable on further downward movement to engage said chuck with the loosely applied cover to insert the latter into sealing engagement with the evacuated container and thereafter to actuate said valve moving means to 30 shut off communication with said vacuum source while venting said chamber to atmosphere.

2. A machine for vacuumizing and closing filled friction top containers, comprising a support for a filled container, a vertically disposed and movable shaft, a pressure chuck secured to said shaft, a sealing head carried by said shaft and movable with the shaft and chuck during part of a downward stroke of the shaft, a source of vacuum communicably connected to said sealing head and a valve housing having an axially reciproca-

ble sliding valve therein disposed between said head and vacuum source, means for moving said valve, a rotatable cam operatively connected to said valve moving means and to said shaft for vertically moving the shaft relative to said container support to move said shaft downwardly to engage said sealing head with the top of a supported container having a loosely applied cover for sealing off a closed chamber including the container head space beneath said loosely applied cover and to thereafter actuate said valve moving means to establish communication between said vacuum source and said chamber to vacuumize the latter, further downward movement of the shaft engaging said chuck with the loosely applied cover to insert the same into sealing engagement with the evacuated container and thereafter to actuate said valve moving means in the opposite direction to shut off communication with said vacuum source while venting said chamber to atmosphere, and means for controlling the extent of downward movement of said shaft to adapt the machine for closing friction top containers of varying heights.

3. A machine for vacuumizing and closing filled friction top containers, comprising a support for a filled container, a vertically movable shaft, a pressure chuck secured to said shaft, a sealing head carried by said shaft and movable therewith and with the chuck during part of a downward stroke of the shaft, a source of vacuum communicably connected to said sealing head and a valve housing having an axially reciprocable sliding valve therein disposed between said head and vacuum source, a pivoted lever connected to said valve for moving the same, a rotary cam

having its peripheral edge engaging said lever and having a cam track operatively connected through a cam roller and rack and pinion connection to said shaft for vertically moving the shaft relative to said container support to move said shaft downwardly to engage said sealing head with the top of a supported container having a loosely applied cover for sealing off a closed chamber including the container head space beneath said loosely applied cover and to thereafter actuate said pivoted lever to establish communication through said valve between said vacuum source and said chamber to vacuumize the latter, further downward movement of the shaft serving to engage said chuck with the loosely applied cover to insert the same into sealing engagement with the evacuated container and to thereafter actuate said pivoted lever in the opposite direction to shut off communication through said valve with said vacuum source while venting said chamber to atmosphere, a clutch controlled power shaft for rotating said cam, lever mechanism connected to said clutch and engageable by a container placed on said support for actuating the clutch to drive said power shaft and said cam for a single revolution only to actuate said sealing head, pressure chuck and valve in timed relation for the purposes described during a single downward movement of said vertically movable shaft, and a rack and pinion connection for controlling the extent of downward movement of said shaft to adapt the machine for closing friction top containers of varying heights.

MILTON E. ROBINSON.
RICHARD N. HENDERSON.
